UNITED STATES PATENT OFFICE.

JULIUS BRENZINGER, OF MOUNT VERNON, NEW YORK, ASSIGNOR TO MAX AMS
MACHINE COMPANY, OF MOUNT VERNON, NEW YORK, A CORPORATION OF
NEW YORK.

CAN-HEADING MACHINE.

1,121,894.

Specification of Letters Patent. Patented Dec. 22, 1914.

Application filed February 24, 1910. Serial No. 545,571.

To all whom it may concern:

Be it known that I, JULIUS BRENZINGER, a citizen of the United States, residing at Mount Vernon, in the county of Westchester and State of New York, have invented certain new and useful Improvements in Can-Heading Machines, of which the following is a specification.

This invention relates to machines for securing the tops and bottoms to the side or body portions of sheet metal containers, commonly known as "tin cans," by what is known as the double-seaming process.

The more common forms of double-seaming machines now in use are each provided with a rotatable support for the can body, and with a rotating chuck which fits in a depression in the top or bottom and not only serves to rotate the can body with said top or bottom held firmly in place for the seaming operation, but supports the edge of the top laterally against the forces of the seaming operation. This operation is most generally performed by two seaming rollers, which are successively brought against the edge of the top or bottom, the first roller serving to fold or curl the edge of the top or bottom around the flange which has been provided at the end edge of the body portion, and the second roller serving to compress the interfolded layers into a substantially solid bead.

It will be apparent that in adjusting a can body, with the top or bottom loosely placed thereon, in the machine, the seaming rollers must be out of the way, and after the can parts have been firmly engaged and are rotating, these rollers must be automatically brought successively into contact with the edge of the can top or bottom. This necessitates the employment of cams or other means for actuating and properly timing operations of the seaming rollers. Furthermore, in addition to the time necessarily lost in bringing the seaming rollers alternately into positions to perform the seaming operation, and thus necessarily limiting the capacity of the machine, the groove with which each of these rollers is provided is necessarily of uniform size and shape throughout its length, the intercurling or interfolding of the flanges being effected by forcing the roller toward the can, thus necessitating a high degree of accuracy of adjustment.

The principal objects of the present invention are, first, to provide a machine which, having seaming mechanism of such character that through the elimination of cams or other means for bringing the seaming mechanism into and out of operative position, may be operated at much greater speed and therefore have a much greater capacity; second, to provide seaming mechanism which is at all times positively held in position for effective operation, whereby all possible danger of the parts getting out of adjustment is absent; third, for the above and other reasons to provide a machine in which the seaming operation is substantially continuous; and, fourth, to provide a double seaming machine which shall be comparatively simple in construction and to the greatest possible extent automatic, efficient and dependable in operation.

My invention will be more readily understood by reference to the accompanying drawings, forming a part of this specification, in which—

Figure 1 is a side elevation of a double seaming machine embodying my invention with parts broken away; Fig. 2 is an enlarged detail elevation of the seaming mechanism; Fig. 3 is a central vertical section of the seaming roller and its support, and Figs. 4 and 5 are detail views showing the successive steps of the seaming operation, with two different forms of seaming rollers.

Referring now to the drawings in detail, numeral 11 refers to a heavy supporting frame having a base 12 which carries the standard 13 in which and said frame 11 the shaft 14 is journaled. At the end of the shaft 14 are mounted the usual fast and loose pulleys 15 and 16, to provide for the transmission of power to the shaft 14 in the usual manner. From the upper end of the frame 11 projects forwardly the arm 17, in the end of which is journaled the vertical shaft 18 which is driven from the shaft 14, by means of the belt 19 connecting the pulley 20 on the shaft 18 with the pulley 21 on the shaft 14 through the interposed idlers 22. At the lower end of the shaft 18 is mounted the head 23 which carries a chuck 24 adapted to fit into a corresponding depression in the top or bottom which is intended to be double-seamed to body portion 25 of the can.

Journalized in the arm 17, just back of the

shaft 18, and in the bracket 26 projecting forwardly from the frame 11, is the vertical shaft 27, upon which is fixed the gear 28 in mesh with the gear 29 on the shaft 18, whereby the two shafts 18 and 27 rotate in unison. Upon this shaft 27 is fixed the inverted cup-shaped member 30, which is adapted to snugly contain the single seaming roller 31. This seaming roller is preferably loose upon the shaft 27, being supported by the collar 42 fixed upon said shaft, and is adapted to slide thereon freely, in and out of the containing member 30. This seaming roller 31 is provided with a continuous spiral groove 32. When this roller is designed to double-seam the top or bottom to the body portion of the can in the manner heretofore performed by two successively operating seaming rollers, this groove 32, while deepest at the beginning thereof, at the lower edge of the roller 31, and gradually becoming shallower as it approaches the upper portion of said roller, is of one uniform width throughout approximately one-half of its length, and uniformly wider throughout the remainder thereof. In this manner, this single roller 31 is provided with a groove which first corresponds in width to the groove in the first of the two seaming rollers heretofore employed, this portion merging into another portion which corresponds in width to that of the groove in the second of the two seaming rollers referred to.

In Fig. 4 I have shown diagrammatically the operation and effect of a spirally grooved seaming roller designed to perform the same character of seaming operation as that heretofore performed by two seaming rollers. In Fig. 5 I have shown the seaming roller 31' provided with a groove the configuration of which varies to meet the requirements for which heretofore three seaming rollers have been successively employed. In this case, it will be noted that the groove, through approximately one-third of its length, has the effect of bending the end of the upper flange around the lower flange, this portion of the groove merging into an intermediate portion where the interfolded flanges are bent toward the body of the can, and this intermediate portion merging into the upper and final portion of the groove which serves to compress the interfolded flanges into a substantially solid bead.

The platform 35, upon which the can body 25 is placed for the seaming operation, is mounted at the upper end of the shaft 36, which is rotatable and slidable longitudinally in bearings in the bracket 37, projecting forwardly from the frame 11. This shaft 36 is vertically reciprocated by means of the hand lever 38 operating through the connecting link 39 to raise and lower the collar 40 so secured to the shaft 36

as to permit rotation thereof. It will therefore be seen that the platform 35 is normally stationary, so that the can body does not begin to rotate until the chuck 24 enters the corresponding depression in the can top and firmly seats said top on the can body. This is important when sealing cans filled with hot liquid or semi-liquid material, portions of which are thrown off by centrifugal force if the can-body is rotated before the top is firmly seated thereon. When the platform 35 is raised, the can-body and its seated top will be rotated with the shaft 18.

It will be apparent that when the can-body with its superposed top is raised through depression of the lever 38, the relation between the container 30 and the seaming roller 31 being normally as indicated in Fig. 3, the first effect produced will be that of engagement between the upper flange 33 of the can top and the bottom of the seaming roller 31, the latter being thereby carried up into the container 30 while the can is raised to that point where the chuck 24 enters the depression in the can top and firmly grips the two parts of the can together. The can body with its top firmly seated thereon is caused to rotate with the chuck 24, and through the medium of the can parts the supporting platform 35 is also caused to rotate at the same speed as the chuck. It will be noted that since the seaming roller 31 is loose on shaft 27, positive rotation will not be imparted to said roller by the rotation of said shaft, although the roller will have a tendency to rotate due to frictional contact with shaft 27 and the container 30. When, however, the can parts have been firmly gripped by the chuck and are caused to rotate therewith, the flanges 33 and 34 will enter and advance in the groove 32, and due to their frictional contact with said groove the roller 31 will be caused to rotate. As has been explained, this groove gradually becomes shallower as it proceeds spirally up the roller 31, whereby the end of the flange 33 is first turned upon itself, each most minute change in the configuration being positively and definitely guided by the changing dimension of said groove. As shown in Fig. 4, the flange 33 is first curled around the end of the flange 34, and as rotation is continued, these superposed layers are folded down against the can-body, as indicated by the dotted lines, the shallowest portion of the groove finally having the effect of compressing the interfolded layers into a substantially solid bead.

It will be apparent, with respect to this seaming roller and its operation, that the roller rotates upon a fixed axis and is always in position for operation. From the instant the superposed flanges enter the lower end of the groove and the can parts are gripped by the chuck, the seaming operation is con-

tinuous until the upper end of the groove is reached, at which time the lever 38 is returned to normal position and the seamed and sealed can body returned with the platform 33, from which it may be removed and another can-body placed thereon for the repetition of the seaming or sealing operation.

I have stated that I prefer that the grooved roller 31 be loose and not be driven upon the shaft 27, and have found in construction the best for all purposes, except that such as the forces of friction which tend to rotate said roller 31 are very easily overcome by the frictional resistance of the assembled can parts at the moment of contact, thus minimizing the danger of displacement of the parts when caused by the sudden application of comparatively violent forces which would if the roller were positively driven. Nevertheless, it is conceivable that under certain conditions it might become desirable to feather said roller on said shaft, whereby the former would be positively driven by the latter and yet be slideable on said shaft for the purpose hereinbefore set forth. Furthermore, the roller 31, being of solid metal, is comparatively heavy, and in overcoming its inertia by the frictional forces of the rotating can parts, suddenly generated and applied when the can top or head reaches and is pressed against the positively rotated check 24, a certain amount of time will be lost, not to speak of the by no means remote possibility of a distortion of the flange of the can top or head in an unanticipated, particularly bending thereof which, on its occurrence, might preclude the formation of a hermetic and otherwise perfect seam. Therefore, I have shown the shaft 27 provided with a spline or key-way 41 which, in the preferred construction and manner of operating the machine illustrated as embodying my invention, serves no useful purpose, but into which a feather may be inserted should it be desired to positively rotate the roller 31, or into which a strip of leather, or other material adapted to increase friction between shaft and roller, may be inserted for the purpose of augmenting the tendency of said roller to rotate under the frictional forces generated by the driven shaft 27 and the member 30 secured thereto, thus minimizing the frictional forces necessary to overcome inertia of the roller.

It will be apparent, with respect to the present invention, that it has the manifest advantages, first, of eliminating the necessity for the provision and operation of a plurality of seaming rollers, with a consequent more complicated reducing mechanism, obviating the necessity for the employment of cams and other mechanisms for insuring properly timed intermittent move-

ment of parts; second, of having a single seaming member the operation of which is continuous, and which, therefore not only permits of operation with great rapidity, but also enables me to absolutely control, from start to finish, the progressive changes in the configuration of the flanges during the process of formation of the seam.

Many modifications of minor details of my improved can heading machine will be readily suggested themselves to those skilled in the art to which it appertains, and I therefore do not desire to limit my invention to the specific construction herein shown and described.

I claim as new and desire to secure by Letters Patent:

1. In a can heading machine, the combination, with rotatable means for supporting the parts to be joined, of a seaming roller, and means for positively rotating one of said elements, said roller being peripherally operable to start and complete the double seam, and said supporting means and said roller having fixed axes of rotation.

2. In a can heading machine, the combination, with means for supporting the parts to be joined, and a seaming roller, of means for imparting relative movement to said elements to establish continuous rolling contact therewith throughout the entire double-seaming operation, said supporting means and said roller having relatively fixed axes.

3. In a can heading machine, the combination, with rotatable means for supporting the parts to be joined, of a seaming roller, and means for positively rotating one of said elements, said roller being peripherally operable to start and complete the double seam by a plurality of continuous relative peripherical rotations of said elements, and said supporting means and said roller having fixed axes of rotation.

4. In a can heading machine, the combination, with means for supporting the parts to be joined, and a seaming roller, of means for imparting relative rotary movement to said elements to establish continuous rolling contact therewith throughout a plurality of relative rotations which conjoin to start and complete the double-seaming operation, said supporting means and said roller having relative fixed axes of rotation.

5. In a can heading machine, the combination, with means for supporting the flanged parts to be joined, of a roller having a continuous seam-forming peripheral groove, and means for imparting relative rotary movement to said elements, said groove being inclined with respect to the plane of relative rotation of said elements and disposed to receive the flanges and retain the same thereon throughout the length thereof.

6. In a can heading machine, the combi-

nation, with means for supporting the flanged parts to be joined, of a roller having a continuous seam-forming peripheral groove of varying cross-sectional configuration, and means for imparting relative rotary movement to said elements, said groove being inclined with respect to the plane of relative rotation of said elements and disposed to receive the flanges and retain the same therein throughout the length thereof.

7. In a can heading machine, the combination, with means for supporting the parts to be joined, of a seaming roller having a spirally arranged seam-forming groove therein.

8. In a can heading machine, the combination, with means for supporting the flanged parts to be joined, of a seaming member, and means for imparting relative rotary movement to said elements, said seaming member being provided with a spiral groove into which the flanges of said parts are directed.

9. In a can heading machine, the combination, with means for supporting the parts to be joined, of a seaming roller having a spiral seam-forming groove therein of varying cross-sectional configuration.

10. In a can heading machine, the combination, with means for supporting the flanged parts to be joined, of a seaming member, and means for imparting relative rotary movement to said elements, said seaming member being provided with a spiral groove of varying cross-sectional configuration into which the flanges of said parts are directed.

11. In a can heading machine, the combination, with a rotating chuck and rotatable means for advancing the assembled flanged can parts and supporting the same against said chuck, of a roller rotatable about a fixed axis and provided with a spiral groove into which the flanges of said parts are directed, said roller being movable axially to retain said flanges in said groove throughout the entire seaming operation.

12. In a can heading machine, the combination, with a rotating chuck and rotatable means for advancing the assembled flanged can parts and supporting the same against said chuck, of a roller rotatable about a fixed axis and provided with a spiral groove of varying cross-sectional configuration into which the flanges of said parts are directed, said roller being movable axially to retain said flanges in said groove throughout the entire seaming operation.

13. In a can heading machine, the combination, with means for supporting the flanged parts to be joined against the forces of the seaming operation, a seaming member, and means for imparting relative movement to said elements to establish continuous rolling contact between said parts and

said member throughout the entire double-seaming operation, said member being provided with a spiral groove, of means for advancing the assembled can parts to and pressing the same against said supporting means and thereby directing the flanges into said groove, and the relative position of said supporting means and said member along the lines of their axes being variable to retain said flanges in said groove.

14. In a can heading machine, the combination, with means for supporting the flanged parts to be joined against the force of the seaming operation, a seaming member, and means for imparting relative movement to said elements to establish continuous rolling contact between said parts and said roller throughout the entire double seaming operation, said member being provided with a spiral groove of varying cross sectional configuration, of means for advancing the assembled can parts to and pressing the same against said supporting means and thereby directing the flanges into said groove, the relative positions of said supporting means and said member along the lines of their axes being variable to retain said flanges in said groove.

15. In a can heading machine, the combination, with a rotatable chuck and rotatable means for advancing the assembled flange can parts and supporting the same against said chuck, of a roller rotatable about a fixed axis and provided with a spiral groove into which the flanges of said parts are directed, said roller being movable axially under action of gravity to retain said flanges in said groove throughout the entire seaming operation.

16. In a can heading machine, the combination, with means for supporting the flanged parts to be joined against the force of the seaming operation, a seaming member, and means for imparting relative movement to said elements to establish continuous rolling contact between said parts and said member throughout the entire double-seaming operation, said member being provided with a spiral groove, of means for advancing the assembled can parts to and pressing the same against said supporting means and thereby directing the flanges into said groove, and said member being mounted for vertical movement along the line of its axis and being lowered under action of gravity to retain said flanges in said groove throughout the entire seaming operation.

17. In a can heading machine, the combination, with means for supporting the flanged parts to be joined against the force of the seaming operation, a seaming member, and means for imparting relative movement to said elements to establish continuous rolling contact between said parts and said member throughout the entire double

seaming operation, said member being mounted for bodily movement vertically and being provided with a spiral groove of varying cross-sectional configuration, of 5 means for advancing the assembled can parts to and pressing the same against said supporting means and thereby raising said member and directing the flanges into said groove, and said member being lowered under 10 the action of gravity to retain said flanges

in said groove throughout the entire seaming operation.

In testimony of the foregoing, I have hereunto set my hand in the presence of two witnesses.

JULIUS BRENZINGER.
